J. R. FERGUSON.

Refrigerator.

No 61529.

Patented Jan. 29, 1867.

United States Patent Office.

JOHN R. FERGUSSON, OF BROOKLYN, NEW YORK.

Letters Patent No. 61,529, dated January 29, 1867.

IMPROVED REFRIGERATOR.

The Schedule referred to in these Letters Patent and making part of the same.

TO ALL WHOM IT MAY CONCERN:

Be it known that I, JOHN R. FERGUSSON, of Brooklyn, in the county of Kings, and State of New York, have invented certain new and useful improvements in "Refrigerators;" and do hereby declare that the following is a full, clear, and exact description thereof, reference being had to the accompanying drawings, and to the letters of reference marked thereon, making part of this specification.

My refrigerator is constructed of the ordinary materials and of the ordinary forms exteriorly. At the centre of the interior is a vertical division channel, D, formed of metal, and divides the refrigerator in two separate parts. Each of said parts is partitioned to form three distinct receptacles for the storage of different articles, (see M, S, R, figs. 1 and 2.) Between the outer walls B and top of the refrigerator A, also the bottom Q, there is an interior wall, P, and between which and the outer, upper, and under walls the air circulates. This refrigerator is provided with two doors, C C, at its front, and a door, J, at the top. E represents the ice box, which is placed near the top of the refrigerator and directly above the division channel D, with the door J leading directly into it. It will be seen that the channel is enlarged at the upper end, forming shoulders for resting the ice box. This box has an opening in its bottom to which is secured the square-shape pipe H, which forms a part of said box. This pipe extends down into the channel D, as shown in fig. 6, and is corrugated at its ends, and provided with a series of openings, d, above the corrugations. F is the ice pan, which I sometimes place within the box E for holding the ice, instead of a slotted board or gate for supporting the ice above the opening at the mouth of the pipe H. The inner walls P P are provided with long and short strips, h, fig. 8, placed at suitable distances from each other, and with a narrow space for the air to pass, while in the ends of the refrigerator there are openings, S' and t, for the ingress and egress of the air. The air is received in the openings S' at each end of the refrigerator and passes in above the top of the upper walls P, and by means of an opening in the rear wall P goes down between the two rear walls, thence under the near receptacle R, and from thence (by means of an opening in the under board) into the air-space under the other receptacle R, thence up behind the wall, over the top of upper wall P, over the other receptacle M, and into a small opening in the door J, where it circulates (over the ice) in the channels in said door, (see s l j, fig. 4,) from thence through a small opening on to the ice, and down through the ice box to the bottom of pipe H, where the corrugations allow the water to drip to the bottom of the channel D, and the air to pass up the intermediate channels N N, fig. 2, to the sides of the chambers M, and through the openings Y there made, and on to the receptacles S S, again to the receptacles R R, and out the openings on their sides, and being slightly rarefied passes and circulates up between the walls P and B, through the opening seen in fig. 3, and out the opening t in the ends of the refrigerator. Upon the receptacles R R, at each side of the channel D, there are gutters with small openings which receive the drippings from the ice and carry the same off by a small spout or other suitable device.

Having thus fully described my invention, what I claim as new, and desire to secure by Letters Patent, is—

The refrigerator box with its openings S' and t, doors C C and J constructed as set forth, receptacles M M, S S, and R R, interior walls P P, channel D, and ice box E, all arranged and used in the manner substantially as herein specified.

J. R. FERGUSSON.
